UNITED STATES PATENT OFFICE

VITALIS M. KLOSS, OF MINNEAPOLIS, MINNESOTA

BOTTLE-CAPPING MACHINE

Application filed November 17, 1928. Serial No. 320,112.

My present invention has for its object the provision of a highly efficient bottle capping machine and more particularly to such a machine for handling milk and cream bottle caps or stoppers of the same general type as disclosed and broadly claimed in my United States Letters Patent 1,638,207 of date August 9, 1927 and entitled "Bottle stopper".

This type of cap or bottle stopper is blanked from stiff paper and thereafter intermediately folded upon itself to form an upstanding rib or flange that affords a finger piece by which the cap may be gripped by the fingers and lifted from its seat in the flange neck of a milk or cream bottle. Said rib or flange also affords a diametrically extended stiffening member for the cap whereby the same may be formed from relatively light paper stock.

The aims of this invention are to provide a capping machine that will successfully and efficiently fold cap blanks of this type as the same are fed into the machine to complete said caps by forming ribs or flanges thereon and thereafter apply the completed caps to seats therefore in the necks of milk or cream bottles as they are successively positioned in the capping machine.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view in elevation of a multiple head bottle capping machine having the invention embodied therein;

Fig. 2 is a view partly in elevation and partly in central vertical section showing one of the heads and its plunger in their lowermost or normal positions and also showing the other movable parts of said head in their timed relation to said plunger;

Fig. 3 is a fragmentary detail view with some parts sectioned on the line 3—3 of Fig. 2;

Fig. 4 is a view corresponding to Fig. 2 with the exception that the head is in its

uppermost position, the plunger in its lowermost position in respect to said head and with the other movable parts of the head in their timed relation to said plunger;

Fig. 5 is a view partly in plan and partly in horizontal section taken on the line 5—5 of Fig. 4;

Fig. 6 is a detail view with some parts sectioned on the line 6—6 of Fig. 4, on an enlarged scale, and also showing one of the cap blanks;

Fig. 7 is a perspective view of one of the completed caps;

Fig. 8 is a view partly in elevation and partly in transverse vertical section taken on the line 8—8 of Fig. 4; and

Fig. 9 is a view partly in elevation and partly in transverse vertical section taken on the line 9—9 of Fig. 4.

The bottle cap A heretofore referred to, primarily as it is cut from stiff paper, comprises a blank B having two semi-circular portions connected by an intermediate portion having in its ends V-shaped notches, as shown in Fig. 6. This blank B is folded upon itself at its intermediate portion to form an upstanding diametrically extended rib or flange C. The formation of this rib C brings the semi-circular portions of the blank B into positions in which they form a complete circle which fits on a seat D in the flanged neck of a milk or cream bottle E. This rib C affords a finger piece which may be gripped between the fingers to lift the cap from its seat D in the bottle E. Said rib C also affords a stiffening member for the cap A. It will be noted that the outer wall of the flanged neck of the bottle E is upwardly tapered.

Referring now in detail to the capping machine illustrated. The same is provided with four complete and independent capping heads, but, of course, the machine may have only one head or any desired number. This machine has a driven central shaft 10 mounted in suitable bearings to turn about a vertical axis. For the purpose of this case, it is not thought necessary to illustrate the driving means for the shaft 10. Rigidly secured to the upper end of the shaft 10 is a bracket having four equally spaced radially extended

arms 11. Supported from each arm 11 is a capping head 12 and under each of said heads is a carrier 13 for one of the bottles E mounted on a conical base 14 for independent raising and lowering movements in respect thereto and the heads 12. The shaft 10 extends through the base 14 at the axis thereof and which base is rigidly secured to said shaft for rotation therewith.

10 Each bottle carrier 13 is provided with a depending stem 15 which projects below the base 14 and has on its lower end a bracket 16 in which a roller 17 is journaled and arranged to travel an endless course on a fixed cam plate 18. Coiled springs 15' encircling the stems 15 are compressed between the base 14 and bracket 16, under strain to retract the bottle carriers 13 in respect to the base 14 and hold the rollers 17 on the cam plate 18. Under the rotary action of the shaft 10 the capping heads 12 and bottle carriers 13 are caused to travel endless courses about the axis of the shaft 10 and one of the caps A is applied to one of the bottles E for each rotation 25 of the shaft 10. The method of positioning the bottles E in capping positions on the bottle carriers 13 and in removed the capped bottles therefrom is well known and need not be considered in this case. The parts thus far 30 described are all of well known and standard construction.

The capping heads 12 are identical the one with the other and hence the description of the one will suffice for the others. Referring 35 now in detail to one of these capping heads 12 the same, as shown, comprises a pair of relatively heavy upper and lower rectangular plates 19 and 20, respectively. These plates 19 and 20 are rigidly but detachably connected by four screws 21 at the corners of said plates and are intermediately connected by a pair of similar screws 22. Said plates 19 and 20 are held vertically spaced at the inner end 40 of the head 12 by a spacing plate 23 and at their outer ends by a pair of spacing washers 24.

The spacing plate 23 extends the full width of the head 12 and is held in place by the inner pair of screws 21 and the screws 22. Said 50 spacing washers 24 encircle the outer pair of screws 21 and are held in place thereby. This spacing of the plates 19 and 20 leaves a shallow passageway 25 therebetween for an intermittently reciprocated cap feeding blade 26.

55 Extending vertically through the head 12 at the inner end portion thereof is a plunger passageway 27. Integrally formed with the upper plate 19 in axial alignment with the plunger passageway 27 is a long upstanding sleeve-like bearing 28 for a vertical movable plunger 29, having on its upper end a short stem 30 which is slidably mounted in the expanded socketed lower end portion 31 of a long upright stem 32.

65 Integrally formed with the lower plate 20

at the under side thereof and in axial alignment with the passageway 27 is a bottle centering member 33. This bottle centering member 33 is in the form of a boss recessed to form an annular bottle engaging surface 34 70 that surrounds the passageway 27 and with which the top of one of the bottles E engages during the capping thereof, see Fig. 4. The annular internal wall centering recess in the member 33 is upwardly and inwardly tapered, 75 to receive the tapered flanged neck of the bottle E. When the flanged neck of the bottle E is moved in the centering member 33, the internally tapered wall thereof engages said flanger neck, moves the bottle E on its carrier 13 with a cam action and axially centers said bottle in respect to the passageway 27.

To further assist in centering a bottle E in respect to the passageway 27 cam-acting lugs 85 35 are formed with the centering member 33, circumferentially spaced therearound on the lower end of said member and form depending extensions thereof. The inner face of the cam lugs 35 have the same taper as the internal wall of the centering member 33. It is only when a bottle E is placed on the carrier 13 considerably out of center that the cam lugs 35 act thereon.

A pair of diametrically extended combined 90 cam and stop pins 36 are anchored to the socketed stem member 31 and extend through vertical slots 37 in the bearing 28. The head 12 is gravity held in its lower most position by the engagement of its bearing 28 at its 100 upper ends of the slots 37 with the pins 36.

The mounting of the cam pins 36 in the slots 37 holds the head 12 from turning about the axis of the stem 32. By reference to Fig. 4, it will be noted that the passageway 27 in the lower plate 20 has the same diameter as the bottle seat D. The socket member 31 is of the same external diameter as the plunger 29 and slidably works in the bearing 28. A cross bar 38, that is square in cross section, 110 extends diametrically through the plunger stem 30 at the upper end of the plunger 29 with its end portions extending through a pair of diametrically opposite vertical slots 39 in the bearing 28 and outward thereof. This bar 38 holds the plunger 29 from turning about its axis in the passageway 27 and by its engagement with the bearing 28, at the ends of the slots 39, limits the stroke of 115 the plunger 29 in respect to the head 12. In the retracted or upper position of the plunger 29, its lower or outer end is flush with the inner face of the plate 19 and when projected it extends into the neck of the bottle E when 120 in the centering member 33.

A coiled spring 40 has one of its ends anchored to a fixed radially projecting pin 41 on the upper end portion of the bearing 28 and its other end is attached to the inner end 130

of the cross bar 38 and is under strain to retract the plunger 29.

The head 12 is yieldingly held suspended by the stem 32, the upper end portion of which extends through a bearing 42 on the outer end of the overlying arm 11 and a bearing 43 overlying the bearing 42, vertically spaced therefrom and integrally formed with a bracket 44 rigidly secured to said arm. A key 45 on the bearing 42 extends into a key-way in the stem 32 and holds said stem from turning about its vertical axis but with freedom for limited endwise sliding movement in the bearings 42 and 43. Applied to the upper end of the stem 32 is an adjusting nut 46 which normally engages the upper end of the bearing 43 and sustains said stem and hence the head 12 from the arm 11. A coiled spring 47 encircling the stem 32 between the bearings 42 and 43 is compressed between the bearing 43 and a cross pin 48 in said stem and yieldingly holds the stem 32 in its normal or lowermost position.

A skeleton magazine is provided for holding a stack of the cap blanks B with the lower end of the stack in an intake passageway 49, formed in the plate 19 at the opposite end thereof from the passageway 27, and supported on the feed plate 26. This passageway 49 in cross section has the same contour as the cap blanks B and holds the same properly positioned to be moved by the feed blade 26 into the passageway 27, as will presently appear.

The magazine 50 comprises, as shown, four upright rods circumferentially spaced around the intake passageway 49, with their lower ends anchored to the head plate 19, for holding the cap blanks B in an upright stack aligned with the passageway 49. A spring-pressed follower 51 is provided for feeding the cap blanks B downward through the magazine 50, into the passageway 49 and onto the feed blade 26. This follower 51 is in the form of a flat disc which rests on the top of the stack of cap blanks B and is provided with a long upstanding stem 52 which works through an aperture in a cross-tie bar 53 and is guided thereby with freedom for endwise movement. A coiled spring encircling the stem 52 is compressed between the follower 51 and cross-tie bar 53 and yieldingly holds said follower pressed onto the stack of cap blanks B. Said cross-tie bar 53 is rigidly secured by pairs of opposing nuts 54 to the upper ends of a pair of upright rods 55 the lower ends of which are anchored in the head plate 19.

The feed blade 26 is reciprocated in timed relation with the plunger 29 to eject the lowermost blank B from the stack and position the same over a thin folding blade 56 which forms the web C to complete the cap A, as will presently appear. This feed blade 26 at the same time it is reciprocated to po-

sition a cap blank B over the folding blade 56 moves the completed cap A from over the folding blade 56 into the passageway 27 under the plunger 29 to be moved thereby into the cap seat D of the bottle E, as will presently appear. To cause the feed blade 26 to eject only a single cap blank B from the stack during its forward movement it is medially recessed at 57 rearward from its inner end portion. This recess 57 is of substantially the same depth and width as one of the cap blanks B and its inner end portion has the same contour as said blank and affords a cap blank engaging shoulder 58.

When the feed blade 26 is in its rearmost position the lowermost cap blank B rests on said blade within the recess 57 and with the rear one-half of its marginal edge portion engaged by the shoulder 58 which holds said blank properly positioned for the folding blade 56. During the forward movement of the feed blade 26 the cap blank B in its recess 57 is ejected from the stack by the shoulder 58 and carried to a position over the folding blade 56. As the lowermost blank B is ejected from the stack the rear end portion of the feed blade 26 moves under said stack and supports the same. In the front end portion of the feed blade 26 is a semi-cylindrical notch 59 the diameter of which is substantially the same as the cap A. The feed blade 26 at its notch 59 is arranged to engage the rear one-half portion of a cap A, after the rib C has been formed on said cap by the folding blade 56, when in its rearmost position and move said cap forward and position the same in the passageway 27 under the plunger 29.

The feed blade 26 is rigidly secured at its longitudinal edges to a pair of cross heads 60 slidably mounted in ways 61 formed in the longitudinal edge portions of the head plates 19 and 20, and supports said blade for straight line traveling movement in the passageway 25. For reciprocating the feed blade 26 in the passageway 25 in timed relation to the plunger 29 there is provided a pair of toggle levers 62 which extend on opposite sides of the bearing 28. Each of these toggle levers 62 comprises a relatively short arm pivoted to a bearing lug 63 on the bearing 28 and a long arm pivoted to and between the prongs of a bifurcated lug 64 on one of the cross heads 60. It will be noted that the long arm of each toggle lever 62 comprises two telescoped sections adjustably connected by screw threads whereby the operative length of the toggle may be varied, at will, to properly position the feed blade 26. For actuating the toggle levers 62 to buckle and straighten the same and thereby reciprocate the cross heads 60, and hence the feed blade 26 there is integrally formed on the short arms of said levers a pair of cam heads 65 which cooperate with the cam pins 36 and are actuated thereby.

Each cam head 65 is provided with paral-

lel cam surfaces 68 and 69 formed on the opposing faces of the prongs of said head and a cam surface 70 which extends at an angle to the cam surface 69 and forms a continuation thereof.

5 The folding blade 56 extends longitudinally of the head 12 on a radial line between the axes of the passageways 27 and 49 and is mounted for vertical reciprocatory movements in timed relation to the plunger 29. This folding blade 56 is rigidly secured to a carrying plate 71 which extends transversely under the head 12 and has at its ends a pair of upstanding arms 72. A pair of short 10 pending posts 73 anchored to the head plate 20 extends through bores in the carrying plate 71 and guides the same for vertical movement. Encircling the posts 73 within recesses 74 in the carrying plate 71 are coiled springs 75 compressed between the head plate 20 and carrying plate 71 to yieldingly hold said carrying plate in its lowermost position with the folding blade 56 retracted. Said folding blade 56 works through longitudinally extended and vertically aligned slots 76 and 77 formed in the head plate 20 and feed blade 26.

Formed in the head plate 19 is a folding groove 78 with which the folding blade 56 cooperates to produce a die adapted to intermediate fold a cap blank B and form the ribs C thereon. This groove 78 is formed in the under side of the head plate 19 and extends the full distance between the passageways 27 and 49 and terminates on the opposite 30 side of the passageway 27 from the passageway 49, see Figs. 2 and 4. Formed in the lower end of the plunger 29 is a diametrically extended groove 79 which is of the same shape and size in cross section as the 35 groove 78. This groove 79 when the plunger 29 is positioned, as shown in Fig. 2, is longitudinally aligned with the groove 78 and forms an intermediate section thereof.

The groove 78 also performs another important function, in that it serves as a guide 45 for a cap A during its movement by the feed blade 26 from a position over the folding blade 56 to the passageway 27 and directs the rib C of said cap into the groove 79 in the 50 plunger 29.

The folding blade 56 is raised against the action of the springs 75 by a pair of laterally spaced cam heads 80 to cause said blade to enter the groove 78 and intermediate fold a cap blank B and form the rib C thereon. These cam heads 80 at their lower ends loosely rest on the top of the head plate 19 as a base of resistance with freedom for compound 55 pivotal and sliding movements longitudinally of the head 12. The upper ends of the cam heads 80 engage the under side of a bearing block 81 detachably secured to the under side of the transverse portion of a yoke 83. This yoke 83 extends transversely of the head 60 12 with its arms overlapping the arms 72 on

the carrying plate 71 and are adjustably but rigidly secured thereto by pairs of set screws 84.

By reference to Fig. 8, it will be noted that the screws 84 extend through slots 85 in the 70 arms of the yoke 81, whereby said yoke may be raised or lowered in respect to the carrying plate 71 to cause the folding blade 56 to enter the groove 78 the proper depth to form the rib C. The cam heads 80 are rigidly connected at their lower end portions by a 75 arm 86 that is in bell crank arrangement therewith and pivoted at 87 to the adjacent end of the bar 38. The cam heads 80 are actuated by the head 12 and plunger 29 to impart reverse reciprocating movement to the feed blade 26 from that of said plunger.

The operation of the improved capping machine may be briefly described as follows:

It may be assumed that the capping head 85 12, which has just been described in detail, has been operated a sufficient number of times to position a cap blank B over the folding blade 56 and a cap A in the passageway 90 27 under the plunger 29 with its rib C in the groove 79 of said plunger. The capping head 12 in normal position is gravity held in its lowermost position with the plunger 29 yieldingly held raised and the feed blade 26 and folding blade 56 retracted. In this position 95 of the feed blade 26, its shoulder 58 engages the lowermost cap blank B which rests on said feed blade and its notched front end 59 is in position to engage a cap A overlying the folding blade 56.

Under the rotation of the capping machine about the axis of the shaft 10 the bottle carriers 13 are successively raised and then lowered as the rollers 17 of said carriers pass over the high portion of the fixed cam head 18 and at which time a cap A is applied to the bottle E on the carrier 13 passing over the high portion of said cam head 18.

As a bottle E is raised by its carrier 13 the flanged neck of said bottle is directed into the centering member 33 and automatically centered thereby in respect to the cap passageway 27 and caused to engage the surface 34 on said member and lift the head 12. As one of the capping heads 12 is lifted by a bottle E the cam heads 65 carried thereby cause their cam surfaces 69 to engage the relatively fixed cam pins 36 and swing said heads on their pivots. This swinging movement of the cam heads 65 buckle the toggle levers 62 and move the feed blade 26 forward. Said forward movement of the feed blade 26 at its notched end engages the cap A positioned over the folding blade 56 and moves the same into the passageway 27 under the plunger 29.

This same forward movement of the feed blade 26, by the engagement of its shoulder 58 with the cap blank B resting thereon, moves said blank and positions the same over the folding blade 56. During the recipro-

cating movement of the feed blade 26 the stack of cap blanks B is supported on the rear end portion of said feed blade. As a cap A and a cap blank B are thus positioned by the feed blade 26 the forward movement of said blade is stopped by the passing of the cam surface 69 out of contact with the cam pins 36. At the time the forward movement of the feed blade 26 is thus stopped the cam heads 65 have been moved into positions in which their cam surfaces 70 are parallel to the slots 37 and as said cam surfaces 70 pass over the cam pins 36 they hold the cam heads 65 stationary and hence the feed blade 26. It is important to note that when the cam heads 65 are stopped in this position the cam surface 68 overlies the cam pins 36, as will presently appear.

During the forward movement of the feed blade 26 under the lifting action of the head 12 the spring 40 has caused the plunger 29 to move upward with said head until stopped by the engagement of the bar 38 with the socket member 31 and at which time the feed blade 26 has reached the limit of its forward movement with a cap blank B and a cap A positioned as above stated.

The plunger 29 is now held fixed in respect to the head 12 and further lifting movement of said head will cause the plunger to enter the passageway 27 and press the underlying cap A into the flanged neck of the bottle E and on to the seat D therein.

As is well known, milk or cream bottles vary somewhat in height and to compensate for such difference the spring 47 will yield under a predetermined pressure on the head 12 and allow said head and all parts carried thereby to lift and thereby insure proper seating of a cap A in the bottle E and prevent breakage of either the bottle or the machine or both.

During the capping action of the plunger 29, the movement of the head 12 in respect thereto will operate the cam heads 80 to lift the carrying plate 71 and thereby project the folding blade 56 through the slot 76 in the feed blade 26 and into the groove 78 to fold the intermediate portion of the overlying cap blank B by pressing the same into said groove to form the rib C thereon. At the completion of the capping of a bottle E said bottle is lowered by its carrier 13 under the action of the cam head 18 and the head 12 follows said bottle under the action of gravity to the limit of its downward movement and thereafter the neck of the bottle E moves out of the centering member 33 to release the same and permit the bottle to be carried away from the capping machine.

During the initial return movement of the head 12 the spring 40 holds the plunger 29 against movement therewith and the movement of the yoke 83 with the head 12 operates the cam heads 80 to release the carrier

plate 71 and permit its spring 75 to move said plate downward and retract the folding blade 56. Further downward movement of the head 12 will cause its bearings 28, at the upper ends of the slots 39 to engage the bar 38 and move the plunger 29 downward with the head 12. During said initial return movement of the head 12 the cam heads 65 are held stationary and hence the feed blade 26 by the contact of the moving cam surfaces 70 over the cam pins 36. At the time the plunger 29 is started on its return movement the cam surfaces 68 engage the cam pins 36 and thereby swing the cam heads 65 on their pivots to straighten the toggle levers 62 and retract the feed blade 26.

The downward movement of the head of 12 is stopped and hence the retracted movement of the feed blade 26 by the engagement of the bearing 28 at the upper end 85 of the slots 37 with the cam pins 36. At the completion of the retracted movement of the feed blade 26 the rear-most cap blank B drops into the recess 57 in the feed blade 26 in position to be engaged by the shoulder 58 during the next operation of the machine to cap a bottle. Also at the completion of the retracting movement of the feed blade 26 the cap A, from the rib C of which the folding blade 95 56 has just been withdrawn, drops into the notched end 59 of said feed blade to be engaged thereby during the next projecting movement of the feed blade 26. In a broad sense, the intake passageway 49 forms a portion or extension of the magazine 50 for holding the cap blanks B.

What I claim is:

1. In a bottle capping machine, a cap applying device, folding means for forming a rib on a cap blank to complete the formation of a cap, and feeding means for feeding a cap blank to the folding means and for feeding a cap from the folding means to the cap applying device.

2. In a bottle capping machine, a head having a cap passageway, means for positioning a bottle in respect to said passageway, cap applying member working in the passageway, folding means for forming a rib on a cap blank to complete the formation of a cap, and means for feeding a cap blank to the folding means and for feeding a cap from the folding means to the cap applying member.

3. In a bottle capping machine a head having a cap passageway, means for positioning a bottle in respect to said passageway, a cap applying member working in the passageway, a die for folding a cap blank to form a rib thereon to complete the formation of a cap, said die comprising a groove in the head and a blade movable into and out of the groove, and means for feeding a cap blank to the die and for feeding a cap from the die to the cap applying member.

4. In a bottle capping machine, a head having a cap passageway, means for positioning a bottle in respect to said passageway, a cap applying plunger working in said passageway, a die for folding a cap blank to form a rib thereon to complete the formation of a cap, said die comprising a groove in the head and a blade movable into and out of the groove, and means for feeding a cap blank to the die and for feeding a cap from the die to the plunger, said groove extending to said passageway and in which groove the rib slides during the movement of the cap from the die to said plunger.

5. The structure defined in claim 4 in which the plunger is provided with a diametrically extended groove arranged to be brought into alignment with the groove of said die to receive the rib therefrom and hold the same during the application of the cap to a bottle by the plunger.

6. In a bottle capping machine, a head having a cap passageway, means for positioning a bottle in respect to said passageway, a cap applying member working in said passageway, folding means for forming a rib on a cap blank to complete the formation of a cap, a magazine on the head for holding cap blanks in a predetermined relation to the folding means, and a feed device for feeding a cap blank from the magazine to the folding means and holding the same in the same position it had in the magazine in respect to the folding means and for feeding a cap from the folding means to the cap applying member.

7. In a bottle capping machine, a head having a cap passageway, means for positioning a bottle in respect to said passageway, a cap applying plunger working in said passageway, a die for folding a cap blank to form a rib thereon to complete the formation of a cap, said die comprising a groove in the head and a cooperating movable blade, a carrier for moving the blade into and out of the groove, yielding means normally holding the carrier with the blade retracted, means actuated by the movements of the head for operating the carrier to project the blade into the groove and for releasing said carrier to its yielding means for retracting the blade, and means for feeding a cap blank to the die and for feeding a cap from the die to the plunger.

8. The structure defined in claim 7 in further combination with means for adjusting the carrier to vary the projecting movement of the blade into the groove.

9. In a bottle capping machine, a head having a cap passageway, means for positioning a bottle in respect to said passageway, a cap applying plunger working in said passageway, a die for folding a cap blank to form a rib thereon to complete the formation of a cap, said die comprising a groove in the head

and a cooperating movable blade, a carrier for moving the blade into and out of the groove, yielding means normally holding the carrier with the blade retracted, a cam movably held in respect to the plunger and arranged to be actuated by movements of the head for operating the carrier to project the blade into the groove and for releasing said carrier to its yielding means for retracting the blade, and means for feeding a cap blank to the die and for feeding a cap from the die to the plunger.

10. In a bottle capping machine, a head having a cap passageway, means for positioning a bottle in respect to said passageway, a cap applying member, folding means for forming a rib on a cap blank to complete the formation of a cap, and a feed member for delivering a cap blank to the folding means in a predetermined position in respect thereto and for feeding a cap from the folding means to the cap applying member.

11. In a bottle capping machine, a head having a cap passageway, means for positioning a bottle in respect to said passageway, a cap applying member working in said passageway, folding means for forming a rib on a cap blank to complete the formation of a cap, a magazine on the head for holding cap blanks in a predetermined position in respect to the folding means, and a feed device arranged to remove a cap blank from the magazine and deliver the same to the folding means without changing its relation thereto, said feed device also being arranged to deliver a cap from the folding means to the cap applying means.

12. In a bottle capping machine, a vertical movable head having a cap passageway, means for positioning a bottle in respect to said passageway, a vertically movable plunger in said passageway, yielding means normally holding the plunger raised in respect to the head, folding means including a movable blade for forming a rib on a cap blank to complete the formation of a cap, a feed member for feeding a cap blank to the folding means and for feeding a cap from the folding means to the plunger, connections actuated by movements of the head for reciprocating the feed blade and the blade of the folding means, an abutment for limiting the lifting movement of the plunger in respect to the head, and means for directing a bottle to the bottle positioning means on the head and for causing the bottle to lift the head and thereby cause the held plunger to apply a cap to the bottle.

13. In a bottle capping machine, a sustaining member a head mounted on said member for raising and lowering movements and normally gravity held in its lowermost position, said head having a cap passageway and means for positioning a bottle in respect thereto, a vertical movable cap applying

plunger mounted in the passageway, yielding means normally holding the plunger raised in respect to the head, said sustaining member acting as a base of resistance for the head and plunger when raised, folding means including a movable member for forming a rib on a cap blank to complete the formation of a cap, a feed device for feeding a cap blank to the folding means and for feeding a cap from the folding means to the plunger, and means for directing a bottle to the bottle positioning means on the head and causing the bottle to lift the head and thereby cause the held plunger to apply a cap to the bottle.

14. The structure defined in claim 13 in further combination with connections actuated by movements of the head to operate the feeding device and folding means.

15. The structure defined in claim 13 in further combination with a toggle lever connecting the feed device to the head, and a cam actuated member on one link of the toggle lever and a relatively fixed cooperating member on the sustaining member for buckling and straightening the toggle lever during the movements of the head to operate the feed device.

16. The structure defined in claim 13 in further combination with a toggle lever connecting the feed device to the head, and a cam actuated member on one link of the toggle lever and a relatively fixed cooperating member on the sustaining member for buckling and straightening the toggle lever during the movements of the head to operate the feed device and for holding the feed device stationary during the application of a cap to a bottle by the plunger.

In testimony whereof I affix my signature.

40 VITALIS M. KLOSS.
